UNITED STATES PATENT OFFICE

GEORGE JOSEPH THOMAS, OF DETROIT, MICHIGAN, ASSIGNOR TO BENDIX BRAKE COMPANY, OF SOUTH BEND, INDIANA, A CORPORATION OF ILLINOIS

BRAKE SHOE

Application filed March 25, 1929. Serial No. 349,746.

This invention relates to brakes, and is illustrated as embodied in an internal expanding automobile brake. An object of the invention is to arrange the brake shoes, or 5 their equivalents, so that the friction surfaces (e. g. of the brake lining) will have a maximum degree of effective engagement with the brake drum.

Having this object in view, I bring the 10 friction surfaces on adjacent shoes, or other friction devices, immediately adjacent each other at the "heels" of the shoes, the necessary "throw" or extent of angular movement of the "heels" of the shoes—i. e. of the ends of 15 the friction surfaces nearest the anchors,—being obtained by positioning each of the anchors well past the end of the other shoe, thus overlapping or "cross-anchoring" the shoes. When possible, the anchor should be 20 set back between the ends of the friction surface of the other shoe.

In the embodiment illustrated in the drawings, the anchored ends of the shoes overlap as described above, while the free ends, arranged adjacent each other across the drum from the anchors, are engaged by an applying device such as a double cam.

Another feature of novelty relates to securing intimate contact of a friction member 25 with the drum, while at the same time retaining control over it to obviate points of infinite pressure with the resultant grabbing characteristics. This I propose to accomplish by making the shoe relatively flexible adjacent its free and applying end where the "wrapping" or "self energizing" effect is the greatest, and further making the anchored end substantially rigid so that applied pressure here is distributed to obviate grabbing. 35 The individual characteristics of a rigid and a flexible shoe are thus combined in a single integral friction device permitting the powerful servo effect and at the same time retaining control of the shoe to obviate grabbing.

A further object of my invention relates 45 to the provision of a shoe having an effective lining contact area of more than 180°, thus minimizing the wear per unit area. As a particular feature of such a shoe, I adjust its position with respect to the brake drum so

that it is eccentric thereto in released position and by virtue of its semi-flexible nature is capable of being fully applied and subsequently fully released. Such a function is impossible with a rigid shoe contacting with 55 the drum over more than 180° thereof inasmuch as such a rigid shoe is incapable of being released.

With my construction I obtain full contact of the relatively long shoe, the point of 60 initial contact being spaced from the applying end of the shoe a distance which is a function of the lining clearance with the shoe released. Subsequent applying pressure effects an application of the flexible end of the 65 shoe, which through its self-energizing action then effects an application of the rigid end of the shoe, thus completing the full lining contact which is the desideratum.

The above and other objects and features 70 of the invention, including various novel combinations of parts and desirable particular constructions, will be apparent from the following description of the illustrative embodiment shown in the accompanying drawings, in which:

Figure 1 is a vertical section through the 75 brake, just inside the head of the brake drum, and showing the shoes in side elevation;

Figure 2 is a partial section on the line 2—2 of Figure 1, showing the anchor arrangement;

Figure 3 is a view similar to Figure 1, the lining being removed to give sufficient 85 space to indicate diagrammatically the action of the shoes; and

Figure 4 is a somewhat modified form of 90 brake comprising a very long semi-flexible shoe and a short rigid shoe, the cross anchor construction remaining the same.

The illustrated embodiment of the invention includes a brake drum 10, at the open side of which is a suitable support such as 95 a backing plate 12, and within which are arranged a plurality of novel shoes or friction devices 14 and 16. Each shoe is shown as T-shaped in cross-section, and is provided with suitable brake lining 18 or other fric- 100

tion material forming a friction face for the shoe.

An important feature of the invention relates to arranging the anchors of the brake so that the shoes overlap each other, thus permitting the adjacent ends of the linings 18 at the "heels" 20 and 22 to be brought very close together. To this end, shoe 14 is anchored on a pivot 24 between the ends of the friction face of shoe 16, the web of shoe 16 being cut away at 26 to permit of this arrangement, while anchor 28 for shoe 16 is similarly arranged between the ends of shoe 14, which is cut away at 30.

15 The brake is applied, against the resistance of a suitable return spring 32, by means such as a double cam 34 arranged across the drum from the anchors 24 and 28. As shown in Figure 4 a spring 33 may also be provided to determine, in conjunction with an eccentric stop 29, the idle position of the shoe.

An important feature of novelty relates to forming the shoes to be relatively flexible 25 adjacent their free ends, where they have their maximum self-energizing or wrapping action by the wedging force of the drum, for example by reducing the depth of the central stiffening flange, while at the same time 30 guarding against "grabbing" by tapering the web toward the anchor until the shoe is substantially rigid at its anchored end. This permits absolute control of the shoe by cam 34 and spring 32, while at the same time 35 there is a high degree of wedging or servo action by the rotating drum on the shoe (on shoe 16 when the drum is turning clockwise, and on shoe 14 when in the opposite direction in the form shown in Figures 1, 40 2 and 3.)

An important object of overlapping the shoes as described above is to bring the heels 20 and 22 as close together as possible,—i. e. to minimize the angle "A",—for the 45 double purpose of securing a greater area of engagement with the drum, and of supporting the entire drum to prevent distortion.

With a two-shoe brake such as selected for 50 illustration, the angular length "B" of the lining on the shoe 16 may be greater than 180°; the greater the length of lining the more effective it will be, while the less will be the clearance at the point 20 (or 22) 55 when the brake is released, with a given angular releasing movement of the shoe. Conversely, the smaller the angle "B" is made, the less effective angular length the lining 60 will have, and the more clearance will be secured when the brake is released.

The approach of the lining (i. e. of point 20 or 22) to the anchor 24 (or 28) is thus definitely limited to a certain minimum angle "C" which will give the necessary clearance 65 when the brake is released. In an ordinary

two-shoe brake, therefore, there is a gap at least double the angle "C" between the ends of the linings on the two shoes, at their anchored ends, instead of the small gap "A" when the novel cross-anchored shoes are used. 70

The nearer anchors 24 and 28 are to the periphery of the drum, the shorter the angle "C" may be made. On the other hand, the nearer the anchors are to the center of the drum, the greater the wedging or "servo" action of the drum on the shoes. In any given case, the radial positions of the anchors will have to be selected according to the wedging or servo action desired, to give as light a 75 pedal pressure as may be desired, whereupon the necessity for a certain clearance at 20 (or 22) will fix the size of the angle "C". 80

A further and very important feature of my invention relates to the virtue of the particular shoe employed in permitting a lining contact of more than 180°. As disclosed in Figure 1 and accentuated in Figure 4, both the shoe and its lining are made more than 85 180° in length, thereby increasing the area of lining in drum contact over that of the conventional shoe. Now it becomes necessary by virtue of such a construction to so construct the shoe as to make it capable of being released from the drum in "brake off" 90 position for with the conventional rigid shoe this is obviously impossible. This is made possible by making one end of the shoe flexible, as previously described. With application of the cam the long shoe first contacts at 95 or about the point D remote from the applying end of the shoe which assumes the position indicated by the dotted lines in Figure 3. Subsequent cam pressure effects a distortion of the flexible end of the shoe into full drum contact whereupon the wedging or wrapping action of the drum effects a 100 movement of said end around the drum forcing the rigid end of the shoe into drum contact. The complete application of more than 105 180° of lining is thus effected, the shoe being fully controllable. 110

In the modification disclosed in Figure 4, the short shoe 15 disclosed is preferably made rigid, thus combining in one brake both rigid and semi-rigid shoes with the resultant advantages flowing therefrom, it being understood that the rigid shoe has advantages such as strength and ease of adjustment not possessed by the flexible type of shoe. 115

While certain illustrative embodiments of my invention have been described in detail, it is not my intention to limit the scope of the invention to those particular embodiments, or otherwise than by the terms of the appended claims. Most of the subject-matter of this application is continued from my prior co-pending applications Serial No. 178,193, filed March 25, 1927, which has now matured into patent No. 1,741,186 and Serial No. 743,- 120 125 130

877 filed October 16, 1924, issued as Patent No. 1,801,397, dated April 21, 1931.

I claim:

1. A brake shoe comprising a rim member and a web member, means adjacent one end of said web member whereby said shoe may be anchored, means adjacent the other end of said web member for engagement by applying means, said web member being of increasing flexibility from said anchoring end to said other end, said shoe extending substantially 180° in length.
2. A brake shoe comprising a rim member and a web member, means adjacent one end of said web member whereby said shoe may be anchored, means adjacent the other end of said web member for engagement by applying

ing means, said web member being of greater radial depth adjacent said anchoring end than adjacent said other end, said shoe extending substantially 180° in length.

3. A brake shoe comprising a rim member and a web member, means at one end of said web member whereby said shoe may be anchored, means at the other end of said web member for engagement by applying means, said web member being flexible at said applying end relatively to said anchoring end, said brake shoe extending substantially 180° in length.

In testimony whereof, I have hereunto signed my name.

80

GEORGE JOSEPH THOMAS.
